UNITED STATES PATENT OFFICE.

JOHN PRIMROSE, OF NEW YORK, N. Y.

LOCOMOTIVE-SUPERHEATER.

1,152,839.

Specification of Letters Patent. Patented Sept. 7, 1915.

Application filed August 5, 1914. Serial No. 855,081.

To all whom it may concern:

Be it known that I, JOHN PRIMROSE, a subject of the King of Great Britain, residing at New York, in the county and State of New York, have invented certain new and useful Improvements in Locomotive-Superheaters, of which the following is a full, clear, and exact description.

The invention which constitutes the subject matter of this application relates to an improvement in superheaters, and has to do particularly with the type of superheater in which the individual units or elements are projected rearwardly from the smoke-box into the fire tubes of the locomotive or other boiler.

The invention resides more particularly in the novel arrangement of the header and elements so that one superheating unit or element, although its end portions be substantially behind other end portions, may be individually removed for repair or replacement without necessarily removing any of the other units.

In the drawings, Figure 1 is a longitudinal section of my device illustrating the relation of the superheater to the smoke-box, fire tube and tube sheet of the boiler. Fig. 2 is a front view of the device taken substantially on the line 2—2 of Fig. 1. Fig. 3 is a top plan view in section of the header illustrating the connection between the header and superheating units, and taken substantially on the line 3—3 of Fig. 1. Figs. 4 and 5 serve to illustrate views, similar to Figs. 1 and 2, of an alternative construction.

Referring to the drawings in detail, and first to Figs. 1 to 3 inclusive, the reference character 10 designates the forward portion of a locomotive or stationary boiler, provided with the usual fire tubes 11, smoke box 12, tube sheet 13 and dry pipe 14. The superheater comprises a saturated steam header 15 into which the dry pipe 14 discharges, the superheated steam header 16, and the superheating elements or units which project rearwardly into the fire tubes 11 and the inlet and outlet ends of which are expanded respectively into the inlet and outlet headers 15 and 16.

The fire tubes are arranged in vertical and horizontal rows as is usual in boiler construction, but only the upper four horizontal rows are utilized, so far as the pres-

ent drawings are concerned, to elucidate the principles of my invention.

In order to explain the invention I show in Fig. 2 three vertical rows of fire tubes and of course a corresponding number of superheater units, and a portion of the latter I designate as A, B, C, D, E, F, G and H. See particularly Fig. 3. It will be obvious that an understanding of how to remove all the units of one vertical row will make it clear how to remove one or more units of other vertical rows, and an explanation of the method of removing the elements will suffice to explain the arrangement whereby such removal may be accomplished. It will also be understood that units E and F of one of the vertical rows correspond to units A and C of an adjacent row, and that units G and H correspond to units B and D. Take the middle row as seen in Figs. 2 and 3, and suppose it is desired to remove unit "A". In this case it is only necessary to disconnect the ends thereof from the headers, turn said ends slightly to the right so that unit C will not be in its path, and withdraw the same between the units C and D. To remove unit B (assuming the others to be in position) disconnect the ends thereof from the headers, turn said ends slightly to the left so that unit D will not be in its path, and withdraw between C and D. To remove C (assuming the other units to be in position) disconnect the ends thereof from the headers, turn the rear end thereof slightly to the left and withdraw this end between the ends of units A and G, which are connected to the superheated steam header. It will be seen that in this case the ends of this unit on the superheater side are unobstructed. It will also be apparent that the rear end of this unit cannot be turned to the right because of the superheated end of unit A. To remove D (assuming the others to be in position) disconnect the ends thereof from the headers, turn the rear end thereof slightly to right and withdraw this end between the ends of units B and E which are connected to the superheated steam header. As in case with unit C, the end of unit D on the superheated side is unobstructed. The rear end of this unit cannot be turned to the left because of the superheated end of unit B.

The ends of units B, C and D are bent outwardly, which, as will be seen, provides

a path or lane for the withdrawal of the upper units. In the case of the unit A, it is not necessary to have its ends bent outwardly because it is uppermost and as will be clearly apparent it could not obstruct any other unit by having its ends straight.

It will be understood of course that the ends of the units A and C are spaced sufficiently far apart from B and D to permit 10 any end to pass between them; that is spaced a distance equal to or slightly greater than the external diameter of the units.

From the foregoing it will be apparent that the end portions are located alternately 15 on opposite sides of a plane defined by the axes of the fire-tubes of each vertical row. In other words, one unit is inclined outwardly from one side of said plane and the succeeding unit is inclined outwardly from 20 the other side of said plane. Furthermore, when the units are removed from the header they are all laterally shifted and in view of this feature, coupled with the fact that a pathway or lane is provided for their withdrawal as previously described, the end portions 25 of the units on one side of said plane may be and preferably are located substantially in front of each other, resulting in great economy of space as compared with 30 that type in which the end portions are so arranged that they are normally out of each other's path.

In Figs. 4 and 5 I show an alternative construction in which the upwardly projecting 35 end portions of the units are expanded into the header chambers with the end portions of the upper two units A and C lying on one side of a vertical plane passing through the axis of said tube, and with the 40 end portions of the lower two units B and D lying on the opposite sides of said plane, and with the said portions on either side lying in front of one another. The construction and arrangement shown in Figs. 45 4 and 5 is such that any unit can be removed from the boiler independently of the others. The lettering of the superheating units is such that the description of Figs. 1 to 3 50 inclusive is applicable to this alternative construction.

What I claim is:

1. The combination with a boiler having a plurality of fire-tubes arranged one above another in substantially the same vertical 55 plane, of a header provided with steam chambers, and superheater units arranged in the fire-tubes and having upwardly projecting end portions which are expanded into said chambers, the end portions of the upper units being located substantially behind the end portions of the lower units, and any of said units adapted to be removed from the boiler independently of the others.

2. The combination with a boiler having 60 a plurality of fire-tubes arranged one above

another in the same vertical plane, of a header provided with steam chambers, and superheater units projecting rearwardly into the fire-tubes and having upwardly projecting end portions which are expanded 70 into said chambers with the end portions of alternate units lying on opposite sides of a plane passing through the axes of said tubes, and with the said portions on either side lying in front of one another, said end portions of any unit adapted to be shifted laterally so that any unit can be removed from the boiler independently of the others.

3. The combination with a boiler having a plurality of fire tubes arranged one above 80 another in the same vertical plane, of a header provided with steam chambers, and superheating units projecting rearwardly into the fire tubes and having upwardly projecting end portions expanded into said 85 chambers substantially in lateral rows, some of the end portions of said rows being located behind and spaced laterally from each other at least a distance equal to the external diameter of said end portions whereby 90 any of said units may be removed independently of the others.

4. The combination with a boiler having a plurality of fire tubes arranged one above 95 another in the same vertical plane, of a header provided with steam chambers, and superheating units projecting rearwardly into the fire tubes and having upwardly projecting end portions expanded into said 100 chambers, said end portions located alternately on the opposite sides of a plane passing through the axes of said fire tubes, said end portions on either side located substantially behind one another and the portions on one side being sufficiently spaced from 105 the portions on the other side to permit any of said portions to be laterally shifted, whereby any one of said units may be removed independently of the others.

5. The combination with a boiler having 110 a plurality of fire tubes arranged one above another in the same vertical plane, of a header provided with steam chambers, and superheating units projecting rearwardly 115 into the fire tubes and having upwardly projecting end portions expanded into said chambers, said end portions located alternately on the opposite sides of a plane passing through the axes of said fire tubes, the end portions on either side located substantially behind each other, but capable of being laterally shifted whereby any unit is independently removable.

6. The combination with a boiler having 120 fire tubes arranged in horizontal and vertical rows, each of the vertical rows comprising at least four fire tubes, of a header provided with steam chambers, and superheater units arranged in the fire tubes and having upwardly projecting end portions 125

130

which are expanded into said chambers, the end portions of the upper units being located substantially behind the end portions of the lower units, and any of said units adapted to be removed from the boiler independently of the others.

7. The combination of a boiler having a plurality of fire tubes arranged in horizontal and vertical rows, each of the vertical rows comprising at least four fire tubes, of a header provided with steam chambers, and superheater units projecting rearwardly into the fire-tubes and having upwardly projecting end portions which are expanded into said chambers with the end portions of alternate units lying on opposite sides of a plane passing through the axes of said tubes, and with the said portions on either side lying in front of one another, said end portions of any unit adapted to be shifted laterally so that any unit can be removed from the boiler independently of the others.

8. The combination with a boiler having a plurality fire tubes arranged in horizontal and vertical rows, each of the vertical rows comprising at least four tubes, of a header provided with steam chambers, and superheating units projecting rearwardly into the fire tubes and having upwardly projecting end portions expanded into said chambers substantially in lateral rows, some of the end portions of said rows being located behind and spaced laterally from each other at least a distance equal to the external diameter of said end portions whereby any of said units may be removed independently of the others.

9. The combination with a boiler having

a plurality of fire tubes arranged in horizontal and vertical rows, each of the vertical rows comprising at least four fire tubes, of a header provided with steam chambers and superheating units projecting rearwardly into the fire tubes and having upwardly projecting end portions expanded into said chambers, said end portions located alternately on the opposite sides of a plane passing through the axes of said fire tubes, said end portions on either side located substantially behind one another and the portions on one side being sufficiently spaced from the portions on the other side to permit any of said portions to be laterally shifted, whereby any one of said units may be removed independently of the others.

10. The combination with a boiler having a plurality of fire tubes arranged in horizontal and vertical rows, each of the vertical rows comprising at least four fire tubes, of a header provided with steam chambers and superheating units projecting rearwardly into the fire tubes and having upwardly projecting end portions expanded into said chambers, said end portions located alternately on the opposite sides of a plane passing through the axes of said fire tubes, the end portions on either side located substantially behind each other, but capable of being laterally shifted whereby any unit is independently removable.

In testimony whereof I affix my signature in the presence of two subscribing witnesses.

JOHN PRIMROSE.
